United States Patent Office

Des. 220,562
Patented Apr. 27, 1971

220,562

BOTTLE OR SIMILAR ARTICLE

Duane J. Quintal, Quezon City, Philippines, assignor to Colgate-Palmolive Company, New York, N.Y.

Filed Mar. 23, 1970, Ser. No. 22,012

Claims priority, application Philippines Sept. 25, 1969

Term of patent 14 years

Int. Cl. D9—01

U.S. Cl. D9—156

FIG. 1

FIG. 2

FIG. 3

FIG. 4

FIG. 1 is a top plan view of a bottle embodying my new design;

FIG. 2 is a side elevational view thereof, the opposite side being the same in appearance as the side shown;

FIG. 3 is an end elevational view thereof, the opposite end being the same in appearance as the end shown; and

FIG. 4 is a bottom plan view thereof.

I claim:

The ornamental design for a bottle or similar article, as shown and described.
